Application June 30, 1941, Serial No. 400,416

2 Claims. (Cl. 101—287)

My invention relates to improvements in printing presses, particularly bed and platen presses of the Gordon type in which both platen and bed are rocked forth and back to and from impression position.

An object of the present invention is to provide a press of the Gordon type having embodied therein simple, durable and inexpensive means interposed between the bed and platen structures and serving efficiently to prevent racking play between the press parts through which the rocking of said bed and platen structures is effected.

Other objects of the invention reside in the novel combination and arrangement of parts and in the details of construction hereinafter illustrated and/or described.

In the drawings, Fig. 1 is a rear elevational view illustrating a bed and platen press in embodiment of the present invention; Fig. 2 is a vertical central sectional view of the structure shown in Fig. 1; Fig. 3 is a vertical sectional view, in detail, taken along the inner face of the press side frame shown in Fig. 2; Fig. 4 is also a vertical sectional view, in detail, the same being taken along the outer face of the side frame and inside of the cam-gear shown in said Fig. 2; Fig. 5 is a detail sectional view taken on the line 5—5 of Fig. 1.

Referring to the drawings, wherein similar parts are designated by similar reference characters throughout the several views, it will be seen that the illustrated press includes side frames 10 connected by cross stays 11. A power shaft 12 journaled in said side frames 10 carries a fly wheel 13 at one end thereof and keyed to said power shaft 12 is a pinion 14, which meshes with a cam-gear wheel 15 fixed to a main shaft 16 journaled in the side frames 10. Trunnioned in said side frames 10 is a platen rocker 17 carrying a platen 18. Secured to a trunnion 19 of said platen rocker 17 is a rocker arm 20 having a cam-roller 21 thereon which travels in the inside-outside cam 22 of the cam-gear 15. This rocker arm 20 serves to oscillate said platen rocker 17 and the platen 18 carried thereby. Back of the side frame 10 is a bed 23 having a form-receiving recess 24 therein and having legs 25 pivoted on a bed shaft 26 mounted at its ends in the lower rear portions of the side frames 10. Journaled in ears 27 projecting rearwardly from the bed 23 is a back shaft 28 to the ends of which are connected side arms 29, 30, side arm 29 being also connected with a crank wheel 31 on the main shaft 16, and side arm 30 being also connected with the cam-gear wheel 15 on said main shaft 16. Power applied to the power shaft 12, as

through a pulley thereon (not shown) causes the platen 18 to tip back and forth from open position (Fig. 2) to closed impression position and causes a relative movement of the bed 23, bringing a form therein against the platen 18 in its impression position and substantially retracting the bed 23 from the platen 18 in the open position of said platen.

The inside-outside cam 22 of the cam-gear 10 wheel 15 has a way 32 for the cam roller 21 on the cam arm 20, said way 32 being formed between an inside cam wall 33 and an outside cam wall 34. Corresponding with the conventional operation of a press of the instant nature, the cam roller 21 occupies a position within the reach 35 of the cam way 32 at its high side, when the platen 18 is disposed in its open position (Fig. 2) and while said cam roller 21 occupies a position within the reach 36 of said cam way 32 at the lower side thereof, the platen 18 is closed in impression position. Operating as in the ordinary press, the cam roller 21 would follow the reach 37 of the cam way 32, riding the outside cam wall 34, and the platen 18 meanwhile would be closed relatively slowly. And said cam roller 21 following the reach 38 of said cam way 32, would ride the inside cam wall 33, breaking the impression and opening the platen rapidly. Thus operating as in the ordinary press, this reversal of movement of the heavy platen 18 and platen rocker 17, coupled with the corresponding reversal of movement of the bed 23 through the side rods 29, 30, would be accompanied with successively opposed stresses in the bearings of the back shaft 28, side rods 29, 30, platen rocker 17, cam-gear shaft 16 and other press parts, as the inside and outside cam walls 33, 34 alternately exert their respective thrusts against the cam roller 21 on the cam arm 20. Resulting from these stresses would be a noisy and injurious racking of the press parts between which room for play might exist. Furthermore, the outside cam wall 34 along the reach 37 of the way 32 and the inside cam wall 33 along the reach 38 of said way 32 would be battered and unduly worn by the cam roller 21, especially after the occurrence of wear in said cam walls and roller. It is the main purpose of my invention to avoid such noisy and injurious racking of press parts and to minimize the wearing of the cam 22 and cam roller 21. In the accomplishment of this purpose, I have incorporated an extremely simple, though highly efficient expedient in bed and platen press construction of the instant character, as will be presently described in detail.

The platen rocker 17 is formed with a conventional locking extension 39, the extremity of which, in the closed position of the platen 18, abuts against the lower portion of the uppermost cross stay 11 between the side frames 10, said extremity of said locking extension, in turn, being engaged at its under side by a rocker lock (not shown) constructed and operating in the usual and well-known manner. As shown in Figs. 1 and 2, said locking extension 39 of said platen rocker 17 has a central slot 40 therein which is provided to afford clearance for a crank 41 on the power shaft 12 and for the piston rod 42 of a pump 43 connected with said crank and employed to create suction in pneumatic mechanisms (not shown) for feeding fresh sheets to the platen and delivering printed sheets therefrom.

In carrying out my invention, lugs 44 are formed on the locking extension 39 at the rear thereof, one lug being located at one side of the clearance slot 40 and one at the other side of said slot. Fitted into aligned bores in said lugs 44 is a pintle 45, each end of which extends beyond its respective lug 44. Interposed between each lug 44 and an end collar 46 removably secured to said pintle 45 is a tiltable bearing 47 formed with a boss or abutment 48 thereon into which a guide rod 49 is threaded. Said rods 49, supported at their forward ends on the locking extension 39 of the platen rocker 17, have a rear support on the legs 25 of the bed 23, said rear support consisting of a rail or cross tie 50 reaching from one of said legs to the other. This rail 50 has two spaced bores therein extending therethrough from front to back thereof and providing eyes 51, one for each of said rods 49, each eye 51 slidably receiving the rear end portion of its respective rod 49 and being flared outwardly both to the front and to the rear, as at 52, 53 (Fig. 5) to admit of relative tilting movements between the rod 49 and rail 50 without undue looseness of the rod within the eye. The front face of the upper portion of the rail 50 is beveled, as at 54, from a line intersecting the axes of the eyes 51 to the upper edge of said rail. Each guide rod 49 is supplied with a collar 55 having a set screw 56 therein, which is normally loosened and free from the rod, said collar in normal usage serving as a washer between the rail 50 and the rear end of a helical spring 56 encircling the rod 49 and compressed between said collar 55 and the abutment boss 48 from which said rod issues.

The springs 56 are applied to the guide rods 49 prior to the application of said rods to the bed rail 50 and locking extension 39 of the platen rocker, the springs 56 in such case being abnormally compressed and their collars 55 being thereupon locked to the guide rods 49 by means of the set screws 56 with said collars serving temporarily as fixed abutments for the rear ends of said springs. After the spring and guide rod assemblies are mounted on the rocker extension 39 and bed rail 50, the set screws 56 are released from the guide rods 49 and the collars 55 are thrust back against the bed rail 50 where they function as end washers for the springs 56, rocking up and down across the longitudinal medial ridge 57 at the front face of the bed rail 50.

When it is desired to remove the spring-equipped guide rods 49 or to render the springs 56 ineffective for any purpose, as for repair, replacement or adjustment of press parts, the collars 55 are pried forwardly on the guide rods 49 against the action of the springs 56 and the screws 56 are set against said rods 49. The

springs 56 are thereupon confined between the then fixed collars 55 and the abutment bosses 48 and are rendered ineffective. The rods 49 with the springs 56 borne thereby and temporarily, abnormally compressed may be readily removed from the press with no interference thereto due to the presence of said springs on said rods.

In the operation of the press, the platen 18 and bed 23 rock toward and away from each other, but since the locking extension 39 and platen 18 are disposed at opposite sides of the center of the platen rocker 17, said locking extension 39 and bed 23 rock forth and back together, there being no substantial directional variation between the two at their points of connection with the guide rods 49 during a complete cycle of the press. Thus the springs 56, backed against the legs 25 of the rocking bed 23 and subjected only to a limited lengthening and shortening thereof, exert a substantially uniform strong pressure against the locking extension 39 of the platen rocker 17. Thereby, the cam roller 21 is caused constantly to ride the inside cam wall 33 of cam-gear 22 eliminating all noise and injury caused by the usual battering of inside and outside cam walls by a cam roller shifting from one cam wall to the other. Other battering and noises in important bearings in the press structure are likewise forestalled, notably in the bearings of the back shaft 28, side rods 29, 30, platen rocker 17, and main shaft 16. The outside cam wall 34 functions chiefly as a safety member.

My invention is highly advantageous in use. The springs 56 require virtually no attention. Being flexed but slightly, they are extremely durable and they are readily installed and removed. The improved press runs quietly and efficiently long after the wearing of parts, which ordinarily would necessitate repair or replacement. Furthermore, the improved press operates efficiently at higher than usual speeds, not only when the press is new, but after the parts become substantially worn, the desirability for platen presses of relatively high speeds being in keeping with the present availability of relatively speedy automatic sheet feeding and delivering mechanisms. The efficiency of operation of my improved press construction is marked by the complete lack of slurring between the impression form and platen upon the making and breaking of the impression, which desirable condition obtains even after substantial wearing of the cam roller 21 and other press parts.

Changes in the specific form of my invention, as herein disclosed, may be made within the scope of what is claimed without departing from the spirit of my invention.

Having described my invention, what I claim as new and desire to protect by Letters Patent is:

1. A press including a frame, an oscillatory platen rocker mounted on said frame and having an extension at one side thereof, a platen carried by said rocker at the side thereof opposite said extension, a rockable bed having supporting legs therefor pivotally mounted on said frame, a power shaft and a main shaft revoluble in the frame, a cam-gear and a crank wheel fixed to said main shaft at opposite sides of said frame, said cam-gear being driven from said power shaft, a back shaft on the bed, side arms connecting said cam-gear and crank wheel with said back shaft, a cam arm on the platen rocker, a cam roller on said arm, said cam-gear having a cam cooperating with said roller, said platen and bed being rocked through said cam arm and side arms oppositely

to tilt the platen and bed back and forth from open to closed relationship, the movement of the rocker extension being generally in the same direction as that of said bed, a pair of abutments pivoted to the back of the rocker extension in horizontal opposition relative to the center thereof, each of said pivoted abutments having a companion abutment on its corresponding bed supporting leg and further having a guide rod issuing therefrom and slidably supported at the extremity thereof by such companion abutment, compression springs encircling said guide rods, each spring being interposed under compression between its respective abutments, said springs acting through said bed and platen rocker yieldingly to hold said cam roller against its said cam and acting further yieldingly to prevent lateral shifting of said platen rocker, back shaft, side arms, and main shaft in their respective bearings.

2. A press including a frame, an oscillatory platen rocker mounted on said frame and having an extension at one side thereof, a platen carried by said rocker at the side thereof opposite said extension, a rockable bed having supporting legs therefor pivotally mounted on said frame, a cam wheel having a cam thereon, a main shaft

in said frame revolvably supporting said cam wheel, means for driving the cam wheel, a back shaft on the bed, a side arm connecting said back shaft with said cam-gear, a cam arm on the platen rocker having a cam roller thereon coacting with said cam, said platen and bed being rocked through said cam arm and side arms oppositely to tilt the bed and platen back and forth from open to closed relationship, the movement of the rocker extension being generally in the same direction as that of said bed, an abutment pivoted to the back of the rocker extension and having a companion abutment carried by a leg of the platen, said pivoted abutment having a guide rod issuing therefrom and slidably supported at the extremity thereof by such companion abutment, a compression spring encircling said guide rod and interposed under compression between said abutments, said spring acting between said bed and platen rocker yieldingly to hold said cam roller against its said cam and acting further yieldingly to prevent lateral shifting of said platen rocker, back shaft, side arm and main shaft in their respective bearings.
